ALOIS KOSSINA, OF ST. LOUIS, MISSOURI.

CARBURETER FEED ATTACHMENT.

1,220,757.

Specification of Letters Patent. Patented Mar. 27, 1917.

Application filed April 8, 1915. Serial No. 19,848.

To all whom it may concern:

Be it known that I, ALOIS KOSSINA, a citizen of the United States, residing at the city of St. Louis, State of Missouri, have invented certain new and useful Improvements 5 in Carbureter Feed Attachments, of which the following is a specification.

This invention relates to carbureter feed attachments. An object of the present invention is to provide an attachment for carbureters whereby steam may flow into the carbureter to mix with air and fuel to facilitate carburation.

Other objects consist in the details of construction and in the combination and arrangement of parts more particularly set forth in this specification and pointed out in the claim.

In the accompanying drawings forming part of this specification wherein like numbers of reference denote like parts wherever they occur,

Figure 1 is a perspective view of the attachment embodying the present invention connected with a carbureter and with the radiator of an automobile, a part of the feed pipe of said attachment being broken away longitudinally to show a sectional view of the drain opening and baffle-plate associated therewith; and

Fig. 2 is an enlarged view, partly in perspective and partly in section, of part of the feed pipe shown as broken away in Fig. 1, and a piece to each side of the baffle-plate therein.

By way of illustration in a device embodying the present invention used in connection with an automobile or the like, a pipe or tube 1 is connected at one end with the casting of carbureter 2 in an appropriate opening therefor whereby said tube communicates with the interior of said carbureter and thence to the manifold 3 of the engine, and the other end of said tube opens into cap-piece 4 of radiator 5, said tube being of any suitable longitudinal configuration, such, for instance, as that shown in Fig. 1 of the accompanying drawings, wherein a horizontal length is connected by means of an elbow 6 or the like to a double curved upwardly extending length therefrom running to said cap-piece 4 as shown in said Fig. 1, the open terminal end of said tube being preferably smaller in diameter than the diameter of 55 said cap-piece and being adapted to enter

slightly into said cap-piece as shown in said drawings.

At any suitable location along tube 1 and intermediate the radiator and the carbureter, an opening 7 is provided in the lower side of said tube, and an upwardly-turned baffle-plate 8 is provided within said tube, said baffle-plate being adapted partially to obstruct the channel of said tube and to extend inwardly and upwardly therein partly 60 across the path of said channel, as shown in the drawings. Said opening 7 and said baffle-plate 8 may be formed by a cut into the under side of said tube transverse its length and toward its center and a portion 70 adjacent said cut and along the direction toward the carbureter may be bent inclined upwardly into said tube, said bent portion forming an obstruction extending partly 75 across the path of the channel of said tube, the incline of said obstruction being upwardly into said tube and away from said carbureter and the mouth of said opening 7 being toward the radiator.

In operation, steam of a greater or less 80 density and hot water entering radiator 5 in the usual manner from the water jacket (not shown) of the engine (not shown) will rise therein and collect near and at the top 85 of said radiator and will flow into the open 90 terminal end of tube 1 from the space about said end in said cap-piece 4, being forced into said open terminal end by the action of the circulation pump (not shown) or by other suitable means or agencies, and will 95 then flow along the interior of said tube toward and into carbureter 2, water condensed from said steam, the cooler water in said tube, and liquid impurities, such, for instance, as oil entering said tube with said steam and water, being drained therefrom through opening 7, but steam therein having a tendency to seek the higher level in said tube will flow onward beyond said 100 baffle-plate 8 toward and into said carbureter, the pressure of air upwardly against steam passing said opening 7 tending particularly to prevent the escape of steam through said opening. Moreover, any solid 105 particles or impurities carried into and along said tube with steam and water will tend to seek the lower level within said tube, and upon reaching opening 7 and baffle-plate 8, will be drained out of said tube 110 through said opening.

The steam, entering carbureter 2, mixes with air and gasoline or the like therein, the temperature of said steam and hot water together with its chemical composition facilitating the process of carburation, and of ignition in the engine cylinder, and the mixture of steam, gasoline or other carbonaceous liquid fuel and air in any desired proportions sprayed through said carbureter forms and produces a gas which flows and is drawn into the cylinders of the engine (not shown) through manifold 3, which gas has improved explosive and ignition properties superior to those of the gas ordinarily introduced into the cylinders of internal combustion engines by the ordinary provisions for carburation of air and carbonaceous liquid fuel through a carbureter as usually equipped.

20 I claim:

A carbureter feed attachment comprising, in combination with the carbureter and

radiator of an automobile, a vapor exhaust pipe leading from the radiator to a point in the rear thereof substantially opposite the carbureter; an L-coupling attached to the lower end of the pipe; and a single unitary pipe connecting the coupling to the carbureter; said connecting pipe having a transverse curved slit in its under side at a point spaced from the coupling and that portion of the pipe, on the side of the slit remote from the coupling being bent upwardly at an inclination toward the coupling end of the pipe to extend within the pipe a distance greater than half the diameter of said pipe to serve as a baffle.

In testimony whereof I hereunto affix my signature in the presence of two witnesses.

ALOIS KOSSINA.
